FREDERIC S. WILLIAMS, OF BROOKLYN, NEW YORK, ASSIGNOR TO FREDERICK KLEIN,
TRUSTEE, OF NEW YORK, N. Y.

LOCK-STITCH SEWING-MACHINE.

1,283,437.

Specification of Letters Patent. Patented Oct. 29, 1918.

Application filed July 21, 1917. Serial No. 181,971.

To all whom it may concern:

Be it known that I, FREDERIC S. WILLIAMS, a citizen of the United States, and resident of Brooklyn, county of Kings, and State of New York, have invented certain new and useful Improvements in Lock-Stitch Sewing-Machines, of which the following is a specification.

My invention relates more particularly to lock-stitch sewing machines provided with a hollow work support across the top of which the work is adapted to be fed by means of suitable mechanism preferably connected with and operating as a presser-foot. A vertically reciprocating needle is provided, adapted to pass through the work and enter the upper end of the hollow work support and form therein, below the work, a loop of the needle thread. In this type of machine, the shuttle or bobbin-hook and the bobbin are located near the lower end of the hollow work-support, and a supplemental hook is provided for drawing the needle-thread loop down into position to be engaged by the looper which I prefer to call a bobbin-hook, the shuttle or bobbin-hook being adapted, in the usual or any suitable manner to pass the bobbin through the loop.

In operating machines of this type, particularly at high speed, it has been found that the long loop of thread required in drawing the loop down into position to be engaged by the bobbin-hook, and by the latter thrown over the bobbin, is apt to become twisted and entangled when it is drawn up by the take-up mechanism to lock the stitch. When this occurs, knots and loops are apt to be formed on the underside of the work, which frequently results in breaking the thread, and sometimes in breaking the needle. This not only produces defective work, but the frequent interruptions from the breaking of thread and needles seriously affects the output of the machine.

The object of my improvement, is to provide means and to so coördinate the mechanism as to eliminate these difficulties and provide a machine capable of producing satisfactory work at high speed operation.

When the eye of the needle is directed transversely of the line of feed of the work, as is usual in this type of sewing machine, and after the bobbin has been passed through the loop and the feed taken place, then during the subsequent drawing up of the long loop

of the needle thread, the thread is drawn over the edge of the groove leading to the eye of the needle with the result that the needle thread is partially untwisted by the strain. Obviously these objections will be more apparent when the machine is operated at high speed. It will be understood that one strand of the long loop of thread is substantially stationary, while the other is rapidly drawn up through the needle by the take-up mechanism to lock the stitch. If twisting of the strands one upon the other occurs, the upgoing strand will tend to draw the other one along with it and thereby form knots and small loops on the underside of the work. The take-up mechanism being adapted to take up a certain length of thread will therefore exert an undue amount of pull upon the needle-thread when such loops or knots are formed, with the result that the thread is weakened and frequently breaks. The strain at times may be so great as to cause the breakage of the needle.

In my improved machine, this difficulty is substantially completely obviated by placing the eye of the needle in the direction of the line of feed of the work, thereby permitting the formation of the needle-thread loop in a vertical plane through the line of feed. I also provide a supplemental hook adapted to oscillate transversely of the line of feed to engage the needle-thread loop at the needle, the supplemental hook being adapted to be moved downward in a substantially vertical plane and to maintain the strands of the loop in parallel relation until engaged by the shuttle or bobbin-hook. By this means, the needle-thread is at no time drawn transversely or angularly across the groove of the needle, thus obviating unequal pressures on the sides of the needle-thread, which as previously explained would tend to cause the thread to untwist slightly. By placing the eye of the needle parallel with the line of feed of the work, it will be seen that at all times the thread is moving in the same plane, which is substantially the plane of the stitch being formed in the work.

In addition to the means hereinbefore referred to, I preferably employ in combination therewith a blade or other suitable means preferably extending from the bobbin-case up into the hollow work-support for positively separating the two strands of the needle-thread loop and guiding the loop

as it is drawn up by the take-up mechanism to complete or lock the stitch. In the form of device shown and described herewith, this comprises a narrow blade of thin sheet metal adapted to extend from the bobbin-case up into the hollow work-support, the upper end of the blade extending practically to the top of the hollow support, or to the underside of the top end thereof through which the needle is adapted to reciprocate. The upper end of the blade is preferably bent along its length, so that the upper and lower portions are substantially at right angles to each other, the upper portion being in a plane substantially parallel with the line of feed or parallel with the stitches as formed. This blade is preferably adapted to be connected with the bobbin-case, and prevent the latter from rotating, the bobbin-case being located central of or on the axis of the oscillating shuttle or bobbin-hook.

The type of lock-stitch glove sewing machine to which my improvements are particularly adaptable, is a machine substantially along the lines of the machine described in the Wilkes Patent No. 1,049,430, of January 7, 1913. The Wilkes' machine, however, while working satisfactorily at low speeds, and with careful handling, is not as satisfactory when run at high speed under commercial requirements. Machines of this type are used for making what are known to the trade as pique gloves, and since in gloves of this type, the seam formed is overlapping, it is particularly necessary that it should be neat in appearance. If knots and loops are formed on the underside of the work, and the thread is frequently broken, it is obvious that a neat seam will not be produced. Therefore, the desirability of obviating these objections and difficulties is apparent and my improvement in the arrangement of the needle to form the loop in a plane through the line of feed and providing means within the hollow work-support for separating the strands of the loop and guiding it as it is drawn up to lock the stitch, have been found to satisfactorily solve these difficulties. The result is that with my improvements, the machine can be run at a high speed and produce satisfactory work.

While I have shown and described my improvements in connection with and as particularly adapted to a glove sewing machine, it will be obvious that by suitable changes in mechanical details, machines of this type can be used for sewing other goods or articles.

One form of my invention is more particularly shown in the accompanying drawings in which Figure 1 represents a side elevation of a lock-stitch glove sewing machine embodying my improvement, certain parts being shown in section. Fig. 2 represents an

enlarged vertical section through the hollow work-support showing the relation of the supplemental hook and the bobbin-hook thereto. Fig. 3 represents a transverse vertical section substantially at right angles to that shown in Fig. 2. Fig. 4 represents in detail, parts of the oscillating hook in its raceway and the lower end of the blade. Fig. 5 represents a view similar to that shown in Fig. 2, except that the parts are in different relative positions. Fig. 6 is a vertical section through the upper end of the hollow work-support at right angles to the view in Fig. 5, showing the parts in the same relative position as shown in Fig. 5. Fig. 7, presents a view similar to that shown in Fig. 5, representing the needle-thread loop drawn down by the supplemental hook into position to be engaged by the oscillating shuttle or bobbin-hook. Fig. 8 is a similar view, showing the needle-thread loop as it is being released from the oscillating bobbin-hook and drawn up the hollow support. Fig. 9 is a top view of the mechanism under the bed plate. Fig. 10 is a similar view to Fig. 9 with some of the parts shown in section or broken away. Fig. 11 is an enlarged detail view of parts at the left in Fig. 10, and Fig. 12 is a detail of a pivot bracket.

Referring to the drawings, and more particularly to Fig. 1 thereof, the machine is represented as provided with bed plate 1 upon which a pillar 2 is mounted, from which extends the usual overhanging arm 3, adapted to support and form bearings for the various mechanisms inclosed therein or mounted thereon. The construction and driving mechanism may be of any preferred form and in the present machine, a drive or pulley wheel 4 provided with the usual fly wheel 5 is attached to the main shaft 6 and adapted to be driven by power in the usual or any preferred manner.

A bracket 7 is mounted upon the arm 3 and provided with means for holding a spool of thread at 8. Another bracket 9 is mounted upon the arm 3 and provided with tension disks 10 and guide members 11 over which the thread from the spool 8 is adapted to pass, as indicated in Fig. 1 of the drawings. A tension spring 12 is also mounted thereon, and guide hooks 13 and 14 through which the needle thread 15 passes on its way to a pulley 16 on the outer end of a lever arm 17 forming the take-up mechanism. This mechanism is substantially the same as that shown and described in the Terwilliger application, Serial No. 31,144, filed May 29, 1915. From the take-up mechanism pulley 16, the needle thread 15 is lead over a pulley 18, fixedly supported on the arm 3 at the outer end thereof, substantially above the needle. From the pulley 18 the thread 15 is conducted downward through a runway 19 and then to and through the eye of the

needle 20. The needle 20, in the herein described form of my improved sewing machine is mounted in the needle bar 21 in such a manner, that a line through the eye of the needle is parallel with the line of feed, or from front to back as viewed in Fig. 1 of the drawings. The arm 3 is also adapted to support a presser foot 22, which in the present instance is utilized, as the feed mechanism for advancing the work, stitch by stitch as required in sewing machines. This feed mechanism is operated by levers 23, and connected with the main shaft 6 within the arm 3 in any suitable or preferred manner. An arm 24 is provided for lifting the feed presser-foot 22 out of contact with the work when so desired. The details of this feed mechanism need not be described here in that they form no part of the present invention.

A hollow work-support 25 is mounted upon the bed 1, being secured thereto by a wide circular flange 26 forming the base of the hollow support. The upper end of the hollow support is preferably slightly conical at 27, and closed by an end piece 28 provided with a hole at 29 through which the needle 20 is adapted to reciprocate. The hollow work-support 25 is preferably substantially cylindrical throughout its length, except for the cone end 27 above referred to, and an enlargement at the back portion thereof near the base, as will be seen at 30 in Fig. 3 of the drawings. By this latter means, the lower or mouth end of the hollow work-support is adapted to provide space for mounting therein a sheet metal blade 31 adapted as hereinafter described, to separate the strands of the needle thread loop and guide the loop as it is drawn up through the hollow support to complete or lock the stitch. The upper end 33 of the blade 31 is preferably bent along its length at right angles to the lower part of the blade, the bend being indicated at 32 in Fig. 3 of the drawings. The upper end 33 of the blade, preferably extends nearly to the end plate 28 at the upper end of the hollow work-support and lies parallel to the line of feed or to the stitches, as will be seen in Fig. 3 of the drawings. The lower end of the blade 31, at 34, is bent outward and then inward upon itself to lie substantially in a vertical plane at right angles to the upper portion 33 of the blade. This vertically disposed lower end 35 of the blade 31 is preferably enlarged or disk shaped, and provided with a hole whereby the blade is mounted upon the bobbin-stud 36 secured to the oscillating looper or bobbin-hook 37, at the axis thereof. The back of the shuttle or bobbin-hook 37 is provided with a tongue member 38 (see Fig. 4), from which the stud 36 projects to the right as seen in Fig. 3 of the drawings, and the stud 36 and the axis of the bobbin and bobbin-hook being preferably parallel with a vertical plane

through the line of feed of the work. By this construction a nearly complete circular opening through the back of the bobbin-hook is formed through which the blade 31 is adapted to pass, while permitting free oscillation of the bobbin-hook. The lower end of the disk portion 35 of the blade is preferably provided with a lug or finger 39, adapted to engage a notch 40 in the edge of the bobbin-case 41, as will be seen in Figs. 3 and 4 of the drawings. Thus the lower end of the blade 31 is fixedly held at the axis of the bobbin-hook and the blade is adapted to prevent rotation of the bobbin-case 41, while the bobbin-hook 37 is permitted to oscillate in the usual manner. Within the bobbin-case 41, there is revolubly mounted a bobbin 42 or other suitable means for providing the under thread for completing the lock-stitch. Preferably, the bobbin thread 43 passes out through a hole at 44 in the bobbin-case and after passing under a suitable tension spring or eye 45, is led up through the tubular work-support to the work, as indicated in Figs. 3 and 8 of the drawings. The bobbin-hook 37 is provided with a hook or point at 46, and is adapted to oscillate in a plane at right angles to a vertical plane through the line of feed of the work. In order that the shuttle or bobbin-hook 37 may oscillate in this manner, it is provided with a flange at 47 adapted to bear in a raceway in an annular bracket 48 secured to and dependent from the underside of the bed plate 1 as indicated in the drawings. The bobbin-hook is preferably held in position in the raceway by plates 49 and 50 secured to the bracket 48 by suitable screws 51, as will be seen from the drawings. The raceway 48 is preferably formed of two parts hinged at 52 so that the lower part thereof may be swung back to release the bobbin-hook 37 in order that the latter, together with the bobbin-case 41 and the blade 31 may be removed. A stud or a bolt 53 is provided for locking the hinged portion of the raceway 48 in normal position with the bobbin-hook in operative position therein, as indicated in Figs. 2, 3 and 11 of the drawings.

The shuttle or bobbin-hook 37 is oscillated at the proper time by a shuttle driver 54 of the usual or any preferred type.

The shuttle or bobbin-hook driver 54 is represented as provided with an arm 55 (see Fig. 4), carrying a collar member 56 adapted to be secured by means of a screw 57 (see Fig. 3) to the enlarged head or end 58 secured to a shaft 59 mounted by means of ball-bearings 60 and 61 in a bracket 62 depending from the underside of the bed plate 1 as indicated in Figs. 3, 9 and 10 of the drawings. The shaft is preferably driven by a pinion 63, secured thereto, which in turn preferably meshes with a segment

- 64, carried on the outer end of a lever 65 (see Fig. 1), pivoted at 66 in a bracket 67, secured to the underside of the bed plate 1, as will be seen in Figs. 1 and 9 of the drawings. The rock lever 65 preferably extends beyond the pivot 66, to form an arm 68, provided with a roller 69 adapted to follow the groove of a cylindrical cam 70, the construction being such that the shuttle or bobbin-hook driver 54 is oscillated in proper synchronization with the needle and other mechanism of the sewing machine. The cylindrical cam 70 is secured to a shaft 71 preferably extending vertically through the pillar 2 and connected to be driven from the main shaft 6 in the usual or any preferred manner.
- I have described the oscillating shuttle or bobbin-hook 37 as located below the mouth 20 or lower end of the tubular work-support 25 in the upper end of which the needle 20 is adapted to reciprocate in order to form within the upper end of the hollow support a needle-thread loop in the ordinary manner. It is necessary, however, before the bobbin can be passed through the loop, for the loop to be drawn down through the hollow support into position to be engaged by the hook 46 of the bobbin-hook 37 which, by oscillating, is adapted to carry the loop over the bobbin-case and thereby pass the bobbin through the loop.
- For this purpose a supplemental hook 72 is preferably provided, as indicated in the drawings (see Figs. 2 and 11) and adapted to slide vertically in slide-ways 73 in a pivoted rock arm 74. The rock arm 74 is preferably provided at its lower end with a stud 75 (see Figs. 3 and 12) provided with a ball 76 secured between the concave ends of screws 77 carried in a fork 78 adjustably secured in the lower end 79 of the bracket 62 hereinbefore referred to as supporting shaft 59 connected with the shuttle driver 54. The supplemental hook member 72 is of sufficient length to reciprocate from a point adjacent the hook 46 of the oscillating bobbin-hook, up into the hollow work support into position to engage the needle-thread loop formed at the needle in the upper end of the work-support as indicated in Fig. 5 of the drawings. The lower end of the hook member at 80 is preferably bent outward and provided with a ball head 81 as represented by dotted lines in Figs. 1 and 2 of the drawings. This ball head 81 is preferably adapted to enter a cylindrical socket 82 on the outer end of a rock lever arm 83 as indicated in Fig. 1 of the drawings. The rock lever arm 83 is preferably pivoted at 84 in a bracket 85 secured to and depending from the underside of the bed plate 1. The rock lever arm 83 is connected with an oppositely extending arm 86 (see Fig. 1) provided with a roller or pin 87, adapted to follow the groove in a

cylindrical cam 88, secured to the lower end of the vertical shaft 71, as indicated in Fig. 1 of the drawings. The bracket 85 is preferably provided with a laterally extending arm or lug 89 adapted to form a bearing support for the shaft 71 (see Fig. 1). The groove in the cam 88 is adapted to oscillate or rock the rock arm 83 at the proper time and the proper distance to carry the hook 72 from the position indicated in Fig. 2 of the drawings up the hollow work-support into position to engage the needle-thread loop at the needle substantially as indicated in Fig. 5 of the drawings.

The supplemental hook 72 is adapted to 80 not only slide up and down in the hollow work-support 25, but, at the proper time, is adapted to be moved bodily about the bearing stud 75 to carry the upper hook thereof out of the path of the needle and the needle-thread loop while the hook 72 is ascending the hollow work-support 25. When the supplemental hook 72 reaches the upper end of the hollow work-support, it is adapted to be moved transversely of the needle-thread loop to engage the latter substantially as indicated by dotted lines in Fig. 5. To give to the supplemental hook 72 this vibrating movement, a collar 90 is pivotally mounted upon a screw stud 91 as indicated in Figs. 2, 3 and 11 of the drawings. A fork 92 is connected to the collar 90 and is slidably and pivotally mounted in a bracket 93 secured to the underside of the bed plate 1, the bracket preferably secured to or forming a part of the shuttle-race bracket 48 hereinbefore referred to, a stud or pin 93^a being provided to act as a pivot in the slot 92^a in the member 92. The opposite end of the fork member 92 is provided in the present instance with a nut 94 adapted to form a socket for a ball-head 95 on the end of a pitman or link 96 pivotally connected at 96^a with a lever or rock arm 97 pivoted at 98 in a bracket 99 secured to and depending from the underside of the bed plate 1 as indicated in Figs. 1, 9 and 10 of the drawings. The rock lever 97 is preferably provided with a suitable pin or roller 100 engaging a groove 101 in the surface cam or disk 102. The cam-disk 102 is secured to the shaft 71 and driven thereby, the relations being such as to move the upper end of the supplemental hook 72 transversely at the proper time.

The supplemental hook 72 is also adapted 120 to be given another movement substantially at right angles to the transverse movement just described. This will be best understood from Figs. 3 and 11 of the drawings, the supplemental hook 72 being adapted to be 125 moved outward and toward the right as shown in Figs. 3 and 11 of the drawings in order that the point 46 of the shuttle or oscillating bobbin hook may pass the hook arm 74 when the shuttle is oscillated to carry 130

the needle thread loop down and pass the bobbin 42 in the bobbin case 41, therethrough. This movement is accomplished by pivoting at 103 in the tubular portion 5 103^a of the bracket 93 a rock lever 104 pivotally connected at 105 (see Fig. 11) with the fork member 92 as indicated in Figs. 2 and 3 of the drawings. By this means it will be seen that the supplemental hook 72, 10 when thrown over toward the left as seen in Fig. 2, will be moved inward or back away from the observer and in position to be moved upward through the hollow work support 25 substantially as indicated in Fig. 5 15 of the drawings. The cam disk 102 is then adapted to move the fork 92 toward the right and thereby swing the supplemental hook 72 into the dotted line position of Fig. 5 and engage the loop of the needle thread 20 at the needle.

When the supplemental hook 72 is drawn down the hollow support 25, the bobbin hook 46 first moves to the position shown in Fig. 7 to engage the needle thread loop. The 25 shuttle or bobbin hook is further oscillated to the position shown in Fig. 8. During the latter part of this movement the member 92 is drawn to the right still farther and the link 104 moves the slide arm 74 outward to 30 clear the shuttle hook 46 as will be seen in Fig. 11 of the drawings.

The operation of my improved machine should be readily understood by those skilled in the art from the above description, but I 35 shall briefly state the operation and trace the movement of the needle thread loop.

When the needle 20 has penetrated the work on the end of the hollow work support, it carries the needle thread down into the 40 hollow work support and then as is usual, the needle starts up and the needle thread loop is formed substantially as indicated in Figs. 5 and 6 of the drawings. The eye being parallel with the line of feed, the loop 45 is formed in a vertical plane through the line of feed. In the drawings (Fig. 5) the loop is slightly displaced to the right to render it visible. The supplemental hook at this time enters or has entered the needle 50 thread loop at the needle as indicated in Fig. 6 of the drawings, and the needle is withdrawn from the work at the same time that the supplemental hook 72 is drawn down through the hollow support to the position indicated in Fig. 7 of the drawings.

In this position, the needle thread loop is shown as engaged by the hook 46 of the shuttle or bobbin hook 37 and is about to be carried off of the supplemental hook 72. The shuttle driver 54 oscillates the bobbin hook to the position indicated in Fig. 8 of the drawings thereby permitting the needle thread loop A to be released from the hook and pass up between 60 the shuttle or bobbin hook and the driver 65

54, the loop, in so doing, inclosing the bobbin thread 43 and the lower end of the blade 31. The take-up mechanism 17 then draws the thread up through the work, the strands of the loop A, being prevented from interference by the blade 31-33, the upgoing strand of the loop adapted to follow along the edge of the blade. The upper end 33 of the blade 31-33 as previously described, is at an angle to the lower end 31 and lies 70 parallel to the line of feed thereby permitting the loop to be drawn off the upper end of the blade in the correct position for completing the stitch. The blade is thus adapted to prevent interference or contact of the 80 rapidly moving upgoing strand of the loop with the strand of the loop connected with the previous stitch. As will be seen in Fig. 5 of the drawings, the upper end 33 of the blade is adapted to move outward toward 85 the hollow work support in order to give clearness for the supplemental hook 72. When, however, the needle thread loop A is being drawn up to close the stitch, the blade assumes the position represented in Figs. 7 90 and 8, the upper end however, being out of line with the path of movement of the reciprocating needle. As the shuttle 37 turns to the position shown in Figs. 8 and 11, the link 104 will cause the hook slide arm 74 to 95 be moved out so that the bobbin hook 46 will pass without interference.

I have found the mechanism of my improved glove sewing machine, as herein described, particularly adapted for high speed 100 operation, the blade 31-33 performing the function of preventing interference between the strands of the loop, thereby assisting in preventing the formation of knots or loops on the underside of the work and permitting 105 more continuous operation of the machine.

It will be understood that I have shown and described one form of my improved device, but obviously, I do not wish to be limited to this form for various modifications 110 in the specific details of construction may be made by those skilled in the art without departing from the spirit and scope of the invention. For instance, the work support in the form of a tube, may, in many instances, 115 be modified and the work supported in any equivalent manner, the other elements of the invention being retained and adapted to the modified form of the work support.

I claim:

1. In a lock-stitch sewing machine provided with take-up mechanism, the combination with a hollow work support in the upper end of which the needle thread loop is adapted to be formed, of means for drawing 125 said loop down through said hollow support and means within said hollow support for separating the strands of the loop while it is being drawn up by said take-up to lock the 130 stitch.

2. In a lock-stitch sewing machine provided with take-up mechanism, the combination with a hollow work support in the upper end of which the needle thread loop is 5 adapted to be formed, of an oscillating bobbin hook near the lower end of said support, a supplemental hook for drawing said loop down into position to be engaged by said bobbin hook and means in said hollow support for separating the strands of the loop while it is being drawn up by said take-up to lock the stitch.

3. In a lock-stitch sewing machine the combination of a hollow work support, a 15 bobbin case, a bobbin hook and a blade or finger secured to said case and extending beyond the circle of movement of said hook, said blade being within said support and adapted to separate the strands of the needle loop after the bobbin has been passed therethrough.

4. In a lock-stitch sewing machine the combination of a hollow work support, a bobbin case and bobbin hook, a supplemental 25 hook adapted to reciprocate to draw the needle thread loop down into the path of said bobbin hook and a blade attached to said bobbin case for separating the strands of the needle loop and preventing them from 30 twisting together as the loop is drawn up after passing the bobbin therethrough.

5. In a lock-stitch sewing machine, the combination of a hollow work support, a bobbin case and bobbin hook, a supplemental 35 hook adapted to reciprocate in said hollow support to draw the needle thread loop down into the path of said bobbin hook and a blade attached to said bobbin case and extending into said hollow support for separating 40 the strands of the needle loop and preventing them from twisting together as the loop is drawn up after passing the bobbin therethrough.

6. In a lock-stitch sewing machine, the 45 combination of a hollow work support through the upper end of which the needle is adapted to reciprocate, a bobbin case, a bobbin hook adapted to oscillate concentrically of said bobbin case, a supplemental 50 hook adapted to reciprocate in said support for drawing the needle thread loop down into position to be engaged by said bobbin hook and a blade extending from said bobbin case into said work support for separating 55 the strands of the needle thread loop after the bobbin has been passed therethrough and while said loop is being drawn up to form the stitch.

7. In a lock-stitch sewing machine, the 60 combination of a hollow work support through the end of which the needle is adapted to reciprocate, a bobbin case, a bobbin hook adapted to oscillate concentrically of said bobbin case, a supplemental hook 65 adapted to reciprocate in said work support

for drawing the needle thread loop down into position to be engaged by said bobbin hook, and a blade connected at one end to said bobbin case and having its free end extending into said work support adjacent to 70 the walls thereof so as to leave a free path for said supplemental hook, said blade being adapted to prevent rotation of said bobbin case and to serve as a guide for the needle thread loop as it is drawn up to form the 75 stitch.

8. In a lock-stitch sewing machine, the combination of a hollow work support through the upper end of which the needle is adapted to reciprocate, an oscillating bobbin hook near the lower end of said support, a bobbin case within and central of the path of movement of said bobbin hook, and a blade having its lower end fixedly held on the bobbin case and adapted to prevent rotation of said bobbin case, the free end of 80 said blade extending into said support and adapted to guide the needle thread loop as it is drawn up to complete the stitch.

9. In a lock-stitch sewing machine the 90 combination of a hollow work support through the upper end of which the needle is adapted to reciprocate, an oscillating bobbin hook near the lower end of said support, a bobbin case within and central of the path 95 of movement of said bobbin hook, and a blade having its lower end transversely of and relatively fixed on the bobbin case, its upper end being free and bent in the direction of its length to be in a plane substantially at right angles to its lower end.

10. In a lock-stitch sewing machine, the combination of a hollow work support through one end of which the needle is 105 adapted to reciprocate, a bobbin hook near the other end of said support, a supplemental hook adapted to reciprocate between the needle and said bobbin hook to carry the needle thread loop to the latter and means within said support for guiding said loop 110 and preventing interference of the strands thereof after the loop leaves the bobbin hook and while it is being drawn up to complete the stitch.

11. In a lock-stitch sewing machine, the 115 combination with a hollow work support of means for forming a needle thread loop in the upper end of said support, a bobbin hook, means for drawing said loop through the work support to said bobbin hook, and 120 means within said support for guiding and controlling said loop after it leaves the bobbin hook and while it is being drawn up to complete the stitch.

12. In a lock-stitch sewing machine, the 125 combination of a hollow work support, adapted at its upper end for the formation therein of the needle thread loop, the lower end being open, an oscillating bobbin hook, a bobbin case within and central of the cir- 130

- cle of motion of said bobbin hook, a supplemental hook adapted to reciprocate into said support and draw the needle thread loop down into position to be taken by said bobbin hook, and a blade extending unattached along the walls of said support to a point near the upper end thereof and adapted to separate the strands of and guide the needle thread loop as it is drawn up to lock the 10 stitch, the lower end of said blade being adapted to prevent rotation of said bobbin case.
13. In a lock-stitch sewing machine, the combination with a needle adapted to form a 15 loop of the needle thread in a vertical plane through the line of feed, of a hollow work support provided with a blade therein, the upper end of which is free and substantially parallel to the plane of said loop and adapted 20 to guide the loop as it is drawn up to lock the stitch.
14. In a lock-stitch sewing machine, the combination with a needle adapted to form a loop of the needle thread in a vertical plane 25 through the line of feed, of a hollow work support, a bobbin hook adapted to oscillate in a plane at right angles to the line of feed, a supplemental hook adapted to enter said support and draw the needle thread loop 30 down into position to be engaged by said bobbin hook, and a blade extending from within the circle of movement of said bobbin hook up into said support and adapted, when said loop is released from the bobbin hook, 35 to guide it to a point near the top of said support.
15. In a lock-stitch sewing machine, the combination of a hollow work support, a needle adapted to enter the top of said support and form a loop in a plane through the 40 line of feed, an oscillating bobbin hook adapted to oscillate in a plane at right angles to the line of feed, a supplemental hook adapted to take said loop at the needle and 45 draw it down into position to be taken by said bobbin hook and a blade within said support adapted to separate and guide the loop as it is drawn up to lock the stitch, the upper end of said blade being parallel with 50 the line of feed and the lower end at right angles thereto, said blade being disposed and supported so as to permit said hooks their respective movements without interference therewith.
- 55 16. In a lock-stitch sewing machine, the combination of a hollow work support, means including a needle adapted for forming the needle thread loop in a vertical plane through the line of feed, means for drawing the loop down through the support to 60 pass the bobbin therethrough, means for drawing the loop up to lock the stitch and means within said support for separating the strands of and guiding the loop as it 65 is drawn up to lock the stitch.
17. In a lock-stitch sewing machine, the combination of a hollow work-support, an oscillating bobbin hook, means adapted to feed the work across the upper end of said support, means for oscillating said bobbin 70 hook transversely of the line of feed, a needle reciprocating into and out of the upper end of said support, the eye of said needle being in the direction of the line of feed of the work, thereby permitting the formation of 75 the needle thread loop in a vertical plane through the line of feed, a supplemental hook adapted to engage said loop at the needle and draw it down into position to be engaged by said bobbin hook, the strands of 80 the loop remaining in the same plane when so drawn down, and means for separating the strands of and guiding the loop as it is drawn up to lock the stitch.
18. In a lock-stitch sewing machine provided with take-up mechanism for drawing the needle thread up to lock the stitch, the combination of a work support, across the upper end of which the work is adapted to be fed, a needle adapted to pass through the 85 work and enter the upper end of said support, the eye of the needle being in the direction of the line of feed of the work, a bobbin hook, a supplemental hook for drawing the needle thread loop down into position to be engaged by said bobbin hook, and a blade in said support for separating the strands of and guiding the loop as it is drawn up to lock the stitch.
19. In a lock-stitch sewing machine, provided with take-up mechanism for drawing up the needle thread loop, the combination of a work support, presser foot means for feeding the work across the top of said support, a reciprocating needle adapted to pass 100 through the work and enter the upper end of said support, the eye of the needle being in the direction of the line of feed of the work, a bobbin hook adapted to oscillate transversely of the line of feed, a supplemental 105 hook, movable vertically, adapted to engage the needle thread loop, a blade extending from the bobbin case upwardly, adapted to separate the strands of and guide the loop as it is drawn up to lock the stitch, the upper 110 ends of said blade being parallel to the line of feed of the work.
20. In a lock-stitch sewing machine, the combination of a work support, means for feeding the work across the upper end thereof, a needle having its eye in the direction of the line of feed of the work, adapted to form a needle thread loop within said support in a vertical plane through the line of feed, an oscillating bobbin hook, a supplemental hook 115 adapted to engage the needle thread loop and draw it down into position to be engaged by said bobbin hook, means for moving said supplemental hook up and down between the 120 needle and the bobbin hook, and means for 125 moving the supplemental hook up and down between the needle and the bobbin hook, and means for 130

moving the upper end of said supplemental hook transversely of the line of feed of the work to engage the needle thread loop at the needle.

- 5 21. In a lock-stitch sewing machine, the combination of a work support, means for feeding the work, a needle having its eye in the direction of the line of feed of the work, adapted to form a needle thread loop within
10 said support in a vertical plane through the line of feed, a bobbin hook, means for oscillating the bobbin hook transversely of the line of feed of the work, a supplemental hook movable longitudinally up and down
15 between the needle and said bobbin hook, means for moving said supplemental hook transversely of the line of feed of the work to engage the needle thread loop at the needle and means for moving said supplemental
20 hook longitudinally to draw the needle thread loop down into position to be engaged by said bobbin hook.

22. In a lock-stitch sewing machine provided with take-up mechanism for drawing

up the needle thread loop, the combination 25 of a work support, means for feeding the work, a needle having its eye in the direction of the line of feed of the work, adapted to form a needle thread loop within the support in a vertical plane through the line of 30 feed, a bobbin hook, means for oscillating the bobbin hook transversely of the line of feed of the work, a supplemental hook movable in a vertical plane between the needle and said bobbin hook to draw the needle thread loop down 35 into position to be engaged by said bobbin hook, means for moving said supplemental hook transversely of the line of feed of the work to engage the needle thread loop at the needle, means for moving said supplemental 40 hook vertically to draw the needle thread loop down to the bobbin hook and means within said support for separating the strands of and guiding the loop as it is drawn up by said take-up to lock the stitch. 45

In testimony whereof I have hereunto set my hand.

FREDERIC S. WILLIAMS.
